UNITED STATES PATENT OFFICE

2,599,243

EMERGENCY DECLUTCHING MECHANISM
FOR CLOTHES WRINGERSCecil W. Feher, Shelton, Conn., assignor to
General Electric Company, a corporation of
New York

Application November 3, 1949, Serial No. 125,217

6 Claims. (Cl. 68—269)

1

This invention relates to an improved clothes wringer safety device of the "instinctive" type, and has for a principal object the provision of a simplified emergency mechanism by which the operator may immediately disconnect the wringer roll driving gear from the drive shaft by pushing or pulling on the wringer frame.

Broadly speaking, emergency devices of this general type are well known. I consider that my invention provides an improved mechanism for translating an angular movement of the wringer frame relative to the wringer head into an appropriate release movement of a detent to free a gear shifting device within the head for return to neutral. In a presently preferred embodiment, I bias the gear shift means to return to neutral position from either of the operating positions at which the direction of rotation of the driven roller of the wringer is established, and utilize a simple detent, such as a spring biased plunger which engages an indexing notch, to maintain the selected drive position. The wringer frame is pivotally supported on the wringer head and has a lever operatively associated with a detent release device which upon rotation by the lever withdraws the detent from its notch. The release device is self-pivoted—that is, side edges of its base portion afford fulcrums about which it may rotate—and hence there is no conventional permanent pivot which may jam or corrode by reason of high humidity, corrosive effect of detergents, and other disadvantageous conditions present during laundering.

My invention is featured by its simplification of manufacturing and assembly operations without sacrifice of reliability, as will be apparent from the following detailed description of the presently preferred embodiment shown in the accompanying drawing in which Fig. 1 is a fragmentary side elevation of a wringer embodying my invention; Fig. 2 is a plan view of the end portion thereof indicating the relatively small angular displacement of the wringer frame necessary to operate the emergency release; Fig. 3 is an end elevation somewhat schematically showing the gear shift lever in neutral; Fig. 4 is a similar view showing the gear shift lever in a drive position and indicating the lift of the detent accompanying displacement of the wringer frame as in Fig. 2; and Fig. 5 is a perspective of the detent release actuator.

Referring now to Fig. 1, the clothes wringer includes a driving head 1 arranged in any suitable fashion for support on a base 2 which may be a structural part of a washing machine (not

2

shown). The wringer frame 3, which may be of any conventional pattern, includes end stiles such as the stile 4 within which are housed upper and lower bearing blocks 5, 6 journaling the shafts of the wringer rolls 7, 8. As is conventional, a top frame member 9 confines a bow spring 10 the ends of which rest upon the top roll bearing blocks to maintain the wringer roll pressure.

The wringer frame is pivotally supported on the head by means such as a bracket 11 secured to the end of stile 4 and affixed to the wringer head by pivot screws 12. I prefer to use non-corrosive materials such as the various die-casting alloys for the head and bracket to insure that the bracket will always be freely swingable on the head. As best appears in Fig. 2 the support bracket 11 is channel-shaped and of substantial width for cooperation with the springs 14 which are socketed in pockets 15 at the sides of the head 1. Springs 14 maintain the normal operating relationship between the frame and head and insure the driving engagement of the lower roll shaft 16 with the drive socket 17.

It will be understood that a power driven shaft S journaled in the head has the usual two drive pinions P, P' slidable thereon and engaging with a crown gear or equivalent G mechanically connected to the drive socket 17. Because this construction may be of any conventional type, for example, that shown in the patent to Samuel I. Gabrielson, 2,561,195, for Clothes Wringer Control Mechanism of the Instinctive Release Type, and assigned to the assignee of the present invention, it has not been detailed herein. It is sufficient to know that a pin 19' projecting eccentrically from a rotatable shaft 19 engages a shift fork F having fingers F' riding in slots in the said pinions. Thus, when a driving connection is to be made with gear G, shaft 19 is rotated to shift fork F' up or down to engage a pinion with a drive pin D projecting from shaft S, according to the desired rotational direction of the lower wringer roll 8.

A sleeve 20 fits over shaft 19 and is rotatably journaled in a collar 21 extending from the wringer head. Diametrically opposed projections 22 of said sleeve fit snugly within pockets provided in the gear shift handle 23. Said handle also receives the polygonal end of shaft 19, and it will be obvious that rotation of handle 23 rotates shaft 19 and sleeve 20 as a unit.

Shaft 19 is biased to a pre-established neutral position by means of a coil spring 24 wrapped about shaft 19 within sleeve 20, and having ends

25 which engage with one of the sleeve projections 22 and a similar projection 26 from the collar 21. The spring ends therefore establish a "home" position of shaft 19 as shown in Fig. 3, because it will be recalled that the sleeve 20 and the shaft 19 are mechanically united by handle 23. Sleeve 20 preferably has three detent notches 27 for cooperation with a detent pin 28 slidably mounted in a bracket 29 projecting from the wringer head and a boss 30 on collar 21, and suitably biased by the spring 31 to be driven into a notch as it comes into registry therewith. The said notches establish operating positions of the shift handle 23. It will be observed from Figs. 3 and 4 that as the handle is rotated to an operating position the spring 24 is placed under tension by the relative displacement of the spring ends at the collar extension 26 and the sleeve extension 22. In such position the detent pin is the sole agency by which the handle 23 and its associated gear shifting device are restrained against return to a neutral position.

The detent release means includes an arm 32 which may be integral with the bracket 11 to extend over the top of the head; said arm terminates on a fork embracing the vertical body portion of a detent release actuator 33. A forked base 34 extending rectangularly from said body portion rests squarely upon the bracket 29 and straddles the detent 28. The legs of the base 34 are provided with side edges 34a and 34b (Fig. 5) which afford fulcrums about which the actuator 33 may be rotated. The body portion of the actuator is pivotally affixed to said detent by a pin 35 which rides within a guide slot 36 provided in a guide wall portion 36a of the wringer head. The pin 35 by slidable engagement with the guide wall portion 36a constrains the actuator 33 against lateral bodily displacement relative to the swinging axis of the frame 3.

The operation of the invention will be apparent from Figs. 3 and 4 in which it clearly appears that angular displacement of the lever 32 will enforce a rotation of the actuator 33 about either of its edges 34a or 34b, causing the detent pin to lift out of its detent notch and release the shift mechanism for return to neutral position under the urging of the spring 24.

It should be kept in mind that emergency release devices on clothes wringers may never be operated, and yet they must be always in condition for operation. Many contemporary devices are subject to the criticism that notwithstanding their protection by masks or exterior casings usually applied to wringers for appearance purposes, operating parts may corrode so that their free movement is affected, with resultant sluggish operation or failure. My emergency device, notably by reason of its simplicity, has a high order of reliability. For example, it will be observed from Figs. 2 and 4 that only a slight angular displacement of the wringer frame is necessary to release the detent. Also it will be seen in Figs. 2 and 3 that the detent release actuator 33 had relatively small surface contact with its supporting wringer head elements. The round-ended walls defining the groove 36 offer little opportunity of corrosive attachment to the actuator, and the contact area between the base legs and the boss 29 is likewise small. The self-pivoting arrangement of the actuator, pursuant to which it rocks about its own base edges 34a and 34b as fulcrums, is more effective than a conventional fixed pivot, and eliminates the danger of freezing present in fixed pivot arrangements.

While I have shown a particular embodiment of my invention, it will be understood, of course, that I do not wish to be limited thereto since many modifications may be made; and I therefore contemplate by the appended claims to cover any such modifications as fall within the true spirit and scope of my invention.

What I claim as new and desire to secure by Letters Patent of the United States is:

1. In a clothes wringer, the combination of a wringer head, frame means swingably carried thereon, wringer rolls journaled in said frame means, drive mechanism within said head and including gear shift mechanism for driving said rolls, means for operating said gear shift mechanism from neutral to a driving position, including a rotary shift actuator, a detent sleeve thereon, and handle means for effecting a conjoint rotation of said actuator and said sleeve, spring means biasing said gear shift actuator to neutral position, a detent carried by said head for rectilinear movement therein, said detent engaging with said sleeve for releasably securing said gear shift in driving position, and means for withdrawing said detent for return of said gear shift to neutral, comprising a member having a body portion extending parallel to the path of movement of said detent and a base portion extending angularly therefrom and carried by said wringer head, said base portion having relatively narrow legs providing fulcrums on either side of said detent path, pin means pivotally interconnecting said detent and said body portion, walls projecting from said wringer head to define a channel parallel to said detent path for slidably receiving said pin means, said walls having end portions engaging with said body portion to support the same, and a lever extending from said frame means and engaging said body portion above the base thereof, whereby to enforce rotation of said detent withdrawing means upon swinging said frame means relative to said head.

2. In a clothes wringer, the combination of a wringer head, frame means swingably carried thereon, wringer rolls journaled in said frame means, drive mechanism within said head and including gear shift mechanism for driving said rolls, means for operating said gear shift mechanism from neutral to a driving position, including a shift actuator, a detent sleeve therefor, and handle means for operating said actuator, spring means biasing said gear shift actuator to neutral, a detent carried by said head for rectilinear movement therein, said detent engaging with said sleeve for releasably securing said gear shift in driving position, and means for withdrawing said detent for return of said gear shift to neutral, comprising a member having a body portion, a base portion extending angularly therefrom and carried by said wringer head, said base portion providing fulcrums at each side of said detent path, pin means pivotally interconnecting said detent and said body portion, walls on said wringer head defining a channel parallel to said detent path, said pin means extending into said channel, and means interconnecting said frame means and said body portion in spaced relationship with the base thereof to enforce rotation of said detent withdrawing member about a base fulcrum and consequent movement of said detent, upon rotation of said frame means relative to said head.

3. In a wringer, the combination of frame means journaling wringer rolls for rotation therein, a wringer head, means for swingably mount-

ing said frame means on said head, drive mechanism within said head for driving said rolls in one of another direction, said mechanism including a gear shift mechanism and means biasing said shift mechanism to neutral position, a detent carried by said head for movement in a fixed path, means biasing said detent into engagement with said shift mechanism to secure the same in driving position, and means for disengaging said detent from said shift means, comprising an angular member having a forked base supported on said head and straddling said detent to provide fulcrums for rotation of said member on said head, a pin pivotally securing said member to said detent above the base of said member, said wringer head having a slot in which said pin rides extending parallel to the path of movement of said detent, and a lever fixed to said frame mounting means and engaging said detent disengaging member, said pin precluding displacement of said member relative to said frame means in the direction of movement of said lever accompanying swinging said frame and thereby constraining said member to rock about one or the other of its fulcrums to enforce axial movement of said detent.

4. In a wringer having wringer rolls, a wringer frame supporting said rolls for rotation, a wringer head, drive mechanism therein including gear shift means for driving said rolls in one or another direction and means including a rotatable shaft to actuate said shift means, said shaft being biased to establish said shift mechanism at neutral, emergency release means for restoring said shift mechanism to neutral from a driving position, comprising means for swingably mounting said frame on said head, a detent pin slidably carried on said head and biased for engagement with said shaft means to releasably restrain the same in driving position, a detent pin actuator pivotally associated with said pin and including a relatively wide base member supported on said wringer head, a lever extending from said wringer frame mounting means and engaging with said detent pin actuator above the base thereof, and means constraining said actuator against bodily displacement in the direction of movement of said lever, whereby said lever movement will enforce a rotation of said actuator about an edge of its base as a fulcrum with resulting translation of the therewith pivotally associated detent pin relative to said shaft means.

5. In a wringer, the combination of frame means, wringer rolls journaled for rotation there-

in, a wringer head, means for swingably mounting said frame on said head, drive mechanism within said head and including gear shift mechanism for driving said rolls in one or another direction, means biasing said gear shift mechanism to return to neutral position, a gear shift detent carried by said head for movement in a fixed path, means biasing said detent to retain said shift mechanism in driving position, and means for operating said detent to release said gear shift, comprising a rigid member rockably carried on said head, said member having a body member and fulcrum-providing base elements disposed on opposite sides of said detent path, means for pivoting said body member to said detent, and a lever extending from said frame mounting and engaging the detent operating means to rock the same about one or the other of its fulcrum members according to the movement of said lever.

6. A clothes wringer, comprising a wringer head, frame means journailling wringer rolls for rotation therein, said frame means being swingably mounted on said wringer head, drive mechanism within said head for driving said rolls in one or another direction, said mechanism including a gear shift biased to neutral position and means to operate said shift to establish the desired driving direction, detent means carried by said head and biased for engagement with said shift means to secure the same in shifted position, a detent actuator rockably supported on said head adjacent said detent, pin means pivotally interconnecting said actuator and said detent, said head having a guide, said pin means slidably engaging said guide to constrain said actuator against lateral bodily displacement relative to the swinging axis of said frame means, and a lever projecting from said frame means and engageable with said actuator to enforce rotation thereof relative to said detent upon movement of said frame means relative to said head.
